UNITED STATES PATENT OFFICE.

WILLIAM S. MOSES, OF TRACY, MINNESOTA.

ROTARY ENGINE.

970,942.

Specification of Letters Patent. Patented Sept. 20, 1910.

Application filed December 2, 1909. Serial No. 530,967.

To all whom it may concern:

Be it known that I, WILLIAM S. MOSES, a citizen of the United States, residing at Tracy, in the county of Lyon and State of Minnesota, have invented certain new and useful Improvements in Rotary Engines; and I do declare the following to be a full, clear, and exact description of the invention, such as will enable others skilled in the art 10 to which it appertains to make and use the same.

This invention relates to rotary engines.

In rotary engines now in use a single feed is employed and when the piston has traveled 180°, or a half revolution, the steam pressure laterally is unduly great and as a consequence, dislocates the piston shaft causing it to yield or spring to one side. As a result of such dislocation of the shaft the 15 piston is caused to bear on one side of the casing thereby causing much friction and wear and causing a space to be left between the opposite side of the casing and piston which allows the steam to escape between 20 the piston and cylinder. To these facts I attribute chiefly the reason why rotary engines prove unsatisfactory or unsuccessful. To overcome the defects above mentioned, I provide a rotary engine wherein the steam 25 30 is simultaneously fed to both sides of the piston, thus equalizing the pressure on both sides of the piston and nearly, if not entirely, doubling the power of the engine. In accomplishing this, the piston is made of 35 approximately elliptical form in longitudinal section to provide two piston heads, while two steam chambers and abutments are employed, being arranged at opposite sides of the engine in the line of rotation. 40 45 With the foregoing and other objects in view, the invention consists of certain novel features of construction, combination and arrangement of parts illustrated in the drawings and particularly pointed out in the appended claims.

In the accompanying drawings: Figure 1 is an end view of an engine embodying my improvements; Fig. 2 is a central longitudinal section thereof; Fig. 3 is a vertical 50 transverse section taken on line 3—3 of Fig. 2; Fig. 4 is a similar view taken on line 4—4 of Fig. 2; Fig. 5 is also a similar view taken on line a—a of Fig. 2; Fig. 6 is a horizontal section taken on line 6—6 of Fig. 3; and 55 Fig. 7 is an oblique section taken on line 7—7 of Fig. 3.

Referring to the drawings for a more particular description of the invention, 1 indicates the casing, which is mounted upon a base 2 of any suitable form, and 3 the rotary 60 piston which is fixedly mounted upon the power shaft 4 and rotates within the casing. This piston comprises a body portion 5 of approximately elliptical form in longitudinal section, leaving the piston heads 6 at 65 opposite sides of the body, the flanges 7 at opposite sides of and extending entirely around the body, and the steam spaces 8 at opposite sides of the piston between said flanges and said heads or body portion. The 70 hollow roller abutments 9 are mounted in the steam chambers 10 at opposite sides of the casing and run in contact with the elliptical portion or body 3 of the piston, said abutments being held at all times in firm 75 contact with the piston by the spring projected headed pins or rods 11, and the steam pressure. The casing is provided at opposite sides with the diagonally disposed inlet ports 12 and 13, and the exhaust ports 14 80 and 15, respectively, which communicate with the exhaust pipes 16 leading away from the casing. Each side of the piston is provided with a pair of oppositely disposed circumferential inlet ports 17 which open out 85 into the steam spaces or channels 8 at opposite sides of the piston by way of the undercut cavities or recesses 18, the inlet ports 17 being of a length to feed steam for about half way of the length of the steam 90 passages 8 so as to allow the steam to act expansively until the exhaust. The admission of the steam to the inlet ports 17 of the piston is by way of the inlet ports 12 and 13 and is controlled by diagonally disposed 95 valves 19 and 20, having the segmental inlet openings 21 and exhaust openings 22. An auxiliary feed may be also provided, whereby the steam may be supplied to drive the piston or to furnish additional power for 100 driving the piston. The steam is supplied to the steam chest 23 by the supply pipe 24 and the distribution of the steam is controlled by the rotary cylindrical valve 25 mounted in the steam chest. The rotation 105 of this valve is properly timed with that of the piston and the means for rotating the valve is the same as that shown in my Patent No. 901,813, patented October 20, 1908. In the present case, the valve itself is somewhat 110 different, however, having the inlet ports 26 and the oppositely disposed openings 27

which simultaneously register and are brought out of registration with the supply pipes 28 leading from opposite sides of the steam chest to opposite sides of the casing 5 at opposite points to supply steam to the passages 12 when the piston is to be driven in a right-handed direction. Branch pipes 29 extend from the pipes 28 to the abutment chambers 10 and to supply steam to the passages 13 when the piston is to be driven in the opposite direction, valves 30 being arranged in said branch pipes to control the passage of the steam. To drive the piston in a right-handed direction the valves 30 in 10 the branch pipes 29 are closed and the valves 19 turned to bring their inlet openings 21 in registration with the inlet passages 12 when steam passes into the steam passages 8 at both sides of the piston between opposite 15 ends of the body of the piston and the abutments, driving the piston in a right-handed direction. Under these conditions, the valves 20 are turned to move their inlet openings out of registration with the passages 13 and to bring their exhaust openings 25 in registration with the exhaust passages 15. When the piston is to be driven in the opposite direction the relative position of the valves 19 and 20 is reversed, as will be understood. From the foregoing it will be seen that the steam is supplied simultaneously to both ends of the piston and not only is lateral strain on the power shaft obviated, but the power of the engine is nearly, if not 30 entirely, doubled.

From the foregoing description taken in connection with the accompanying drawings, the construction and operation of the invention will be readily understood without 40 requiring a more extended explanation.

Various changes in the form, proportion and the minor details of construction may be resorted to without departing from the principle or sacrificing any of the advantages of the invention, as defined in the appended claims.

I claim as my invention:—

1. In a rotary engine, a cylindrical casing, a piston comprising a body portion of approximately elliptical form in longitudinal section leaving piston heads at opposite ends of the body portion, side flanges and steam passages on opposite sides of said body portion between said flanges, said piston also 50 having a pair of circumferential inlet ports at each side, having undercut cavities or channels leading to the steam passages, roller abutments mounted at each side of the casing and working against the elliptical body 55 portion of the piston, means for feeding steam to the circumferential ports at either 60

side of the piston heads, and means for controlling the exhaust of the steam.

2. In a rotary engine, a cylindrical casing, a piston comprising a body portion of approximately elliptical form in longitudinal section leaving piston heads at opposite ends of the body portion, side flanges and steam passages on opposite sides of said body portion between said flanges, said piston also 65 having a pair of circumferential inlet ports at each side having undercut cavities or channels leading to the steam passages, roller abutments mounted at each side of the casing and working against the body portion of the 70 piston, means for feeding steam to the circumferential ports at either side of the piston, means for controlling the exhaust of the steam, and resilient means for holding the abutments in contact with the body portion 75 of the piston.

3. In a rotary engine, a cylindrical casing, a piston comprising a body portion of approximately elliptical form in longitudinal section leaving piston heads at opposite ends 85 of the body portion, side flanges and steam passages on opposite sides of said body portion between said flanges, said piston also having a pair of circumferential inlet ports at each side having undercut cavities or 90 channels leading to the steam passages, roller abutments mounted at each side of the casing and working opposingly against the body portion of the piston, means for feeding steam to the circumferential ports at either 95 side of the piston, means for controlling the exhaust of the steam, and spring projected pins for holding the abutments in contact with the body portion of the piston.

4. In a rotary engine, a cylindrical casing, 100 a piston comprising a body portion of approximately elliptical form in longitudinal section leaving piston heads at opposite ends of the body portion, side flanges and steam 105 passages on opposite sides of said body portion between said flanges, roller abutments mounted at opposite sides of the casing and working opposingly against the piston, means for simultaneously feeding steam to both 110 steam passages at opposite sides of the piston, means for controlling the feed and exhaust of the steam and spring-projected means for holding the abutments in contact with the piston.

In testimony whereof I have hereunto set 115 my hand in presence of two subscribing witnesses.

WILLIAM S. MOSES.
